(57) **CLAIM**

The ornamental design for a smart chip housing, as shown and described.

DESCRIPTION

FIG. 1 is a perspective view from the top-right of the smart chip housing;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a perspective view from the bottom-right thereof.

The features shown in broken lines are for the purpose of illustrating portions of the article that form no part of the claimed design.

1 Claim, 8 Drawing Sheets
